UNITED STATES PATENT OFFICE.

EDWIN AUGUSTUS BYRDE, OF NAGPUR, CENTRAL INDIA.

RAILWAY OR TRAMWAY RAIL JOINT.

Application filed January 7, 1925, Serial No. 963, and in British India October 14, 1924.

This invention has reference to improvements in rail butt joints to allow for expansion and contraction to minimize the action of creep, and to secure greater smoothness in 5 travelling.

It is characterized in that the ends of the rails are supported on a sole or bottom plate, preferably strengthened by ribs, said plate acting as a girder and being itself secured by 10 bolts at its ends to top plates resting on the foot of the rail. The top plates are adapted to keep both rails in true alignment by direct contact with the web of the rail when the bolts used therewith are tightened. 15 These top plates are held in position by projections from the bottom plate. Expansion and contraction may be provided for in the bolt holes through the foot of the rail.

I am aware that it has heretofore been proposed to rest the ends of the rail on bearing plates supported on sleepers. I am also aware that the common forms of unsupported joints depend on the rigid contact between the head and foot of the rail formed by fish 25 plates bolted together through the web of the rail. My invention on the other hand constitutes an improvement in that the two ends of the rails rest on a flat surface keeping them truly level and the tendency to 30 wear that occurs in the contact surfaces of rails and fish plates is entirely eliminated. It also may give greater supporting strength at the point where most strength is required i. e. at the junction point of the rails. The 35 device gives, moreover, increased resistance to horizontal bending action at the joint, whilst allowing for freer expansion and contraction as the bolts are not required to be tightened to more than the extent usual for 40 fish bolts of ordinary fish-plated rail joints.

The invention consists of means for joining railway or like rails comprising a bottom plate upon which the ends of the rails to be joined rest and over which said rail ends 45 butt together, and two upper plates adapted to be bolted down to the said bottom plate and to engage the webs or the two rail ends and/or the upper part of the bottom flange or lower heads of the rails and also to contact upon or against suitable projections or 50 supporting surfaces on the said bottom plate.

The invention not only embraces the joint but also the component parts therefor.

The invention will now be described with reference to the accompanying drawings in 55 which like numbers of reference indicate like parts throughout, and in which:—

Figure 1 is part elevation and part longitudinal section of one convenient form the joint may take when applied to flat-footed 60 rails.

Figure 2 shows on the right a half cross section on line AA of Figure 1 and on the left a half cross section on line BB of Figure 1. 65

Figures 3 and 4 are corresponding views of a convenient form the joint may take when applied to bull-headed rails.

Referring to Figures 1 and 2 the rails to be joined have heads 1, webs 2 and flanges 3. 70

The two rail ends rest upon the bottom plate 4 and are butted together thereon. The bottom plate 4, in the example illustrated, has three downwardly extending ribs 5, 5, which preferably will be of maximum depth 75 at 5^a at the centre of the joint, tapering away towards the extreme ends 5^b. The bottom plates are provided with upwardly extending longitudinal ribs 6, 6 along each upper outer edge. 80

Two upper plates 7, 7, are used. The outer edges 7^a, 7^a, of these upper plates make contact with the ribs 6, 6, and the inner edges 7^b, 7^b, press against the webs 2 of the rail ends to be joined. 85

Bolts 8, 8, preferably four in number, one at each end of each upper plate 7, are adapted to bolt the parts together. On tightening these bolts the corners 7^c, 7^c, of the upper plates are forced against the ribs 6, 6, and the inner edges 7^b, 7^b, preferably turning about these corners, or some surface adjacent thereto, hold the webs of the two rail ends in proper alignment. At the same time the bottom surfaces 7^d, 7^d of the upper plates 95 press upon the upper surfaces of the rail foot 3 and hold the parts firmly down onto the bottom plate 4. A space 9 is left between each upper plate and the foot or flange of the rail and it will be seen that 100 these upper plates act as arches.

The holes 10 in the flanges of the rails or in the parts 4, 7, 7 may be slotted or made larger than the bolts 8, 8 to allow for the expansion and contraction of the rails. 105

In the embodiment illustrated in Figures

3 and 4 the construction is in most respects similar to that described with reference to Figures 1 and 2, but modified to suit a bull-headed rail.

5 The lower head 3 of this rail may be depressed and rest in a depression 4^a in the bottom plate 4.

10 The upwardly projecting longitudinal ribs or projections 6, 6, along the edges of the bottom plate 4 may have inclined supporting surfaces 6^a, 6^a, adapted to each present a sort of skew-back for supporting the outer edges of the upper plate 7, 7.

15 The thrust of the arching action produced in these plates may thus be more efficiently transmitted into the ribs 6, 6.

20 In Figure 4 it will be seen that instead of the surfaces 7^a which press the foot of the rail down upon the bottom plate 4 being towards the outside as shown in Figure 2 these contact surfaces may be on the inner side at 7^c 7^c.

25 The bevel or incline 6^a is an important feature as with its assistance a wedging action may be developed which assists in taking up any slack. For example, owing to the fact that a certain rolling margin must be allowed due to the wear of the rolls in manufacturing the rails the dimensions of the parts are not exact and the incline 6^a allows of the necessary accommodation of the parts to each other.

30 It will be noted that the downwardly projecting ribs, 5, 5, particularly where they are deepest at 5^a the centre of the joint taken in conjunction with the upwardly extending ribs 6, 6 increase the vertical depth of the bottom plate 4 and add very considerably to its strength and stiffness in the vertical direction.

35 Also the fact that the bottom plate 4 is wider than the rail flange 3 and at its side edges has a concentration of metal constituted by the ribs 6 and outer of the ribs 5 adds enormously to the lateral stiffness of the joint, making the joint far stronger laterally than is usual.

40 The ribs 5, 5 also provide depressions or grooves into which the heads of the bolts 8 fit, thus preventing the bolts turning when the nuts are being screwed on.

45 It will be understood that the invention is not restricted to the exact embodiment shown, but includes within its scope reasonable modifications. For example, the rib 6 is preferably continuous, but may have knobs thereon to afford a better or larger supporting surface for the outer edges of the plates 7, 7. The shape and dimensions of the parts 50 may be considerably altered, if desired.

55 The essential feature is to provide a rail joint in which the ends of the rails are supported and rest directly on a plate secured at its ends to the rails themselves by being bolted to top plates resting on the foot of the

60 rail. In this joint the top plates are adapted to keep both rails in true alignment by direct contact mainly with the web of the rail when the bolts used therewith are tightened, and these top plates are held in position by projections from the bottom plate. The whole forms a rigid joint keeping both rails truly level and truly aligned, without offering undue resistance to expansion and contraction. The joint is capable of withstanding the 70 load of fast running trains with the minimum of shock, and is adapted to give maximum life to the wearing parts themselves.

75 The rail joint as above described is one which can function to reduce the tendency of 80 the rails to creep. This creeping movement cannot develop to any marked extent before one end of the bottom plate butts up against the side edge of a sleeper, and this added resistance is very effective in resisting further movement.

85 The joint arrangement is one having considerable solidity and may be so constructed that it will function to render the closer spacing of sleepers at the joints unnecessary. A 90 saving of 4% in the total number of sleepers used may thus be effected.

95 Having now particularly described and ascertained the nature of my said invention and in what manner the same is to be performed, I declare that what I claim is:—

100 1. A structure for joining railway rails, comprising an upper arch plate bolted to a lower girder plate over the flange of the rail-ends, the inner edge of said upper plate having for its skew-back the web of the rail, and the outer edge of said upper plate having for its skew-back, an upward extension of the bottom plate and also alternatively contacting upon the rail flange, in such a fashion 105 that when the plate is set up upon, arch action will ensue between the upper plate, the rail, and the bottom plate, to such an extent that the rail-ends will be held more firmly in alignment and will be held more firmly upon 110 the bottom plate.

115 2. A structure for joining railway rails, comprising an upper arch plate bolted to a lower girder plate over the flange of the rail-ends, the inner edge of said upper plate having for its skew-back the web of the rail and also alternatively contacting upon the rail flange, and the outer edge of the upper plate having for its skew-back an upward extension of said bottom plate.

120 3. A structure as in claim 1, wherein two upper plates, when bolted down in position upon the rail-ends have their outer edges forced into intimate contact with raised outer supporting surfaces formed by the upward extension of the bottom plate to such a degree that the inner edges of said upper plates press firmly upon the webs of the two rail-ends to hold said ends in alignment.

125 4. A structure as in claim 1 wherein two 130

upper plates when bolted in position upon the rail-ends have at least one of their ends pressed downwardly upon said rail-ends to a degree sufficient to hold them rigidly in contact with said bottom plate.

5. A combination as claimed in claim 1, whereby the rail-ends are rigidly supported

from beneath the lower surfaces of the rail-ends and the rail-ends are held in alignment by pressure applied by said support on the lower ends of the webs.

In testimony whereof I hereto affix my signature, this second day of December 1924.

EDWIN AUGUSTUS BYRDE.
